APPARATUS FOR HEATING COAL

John Stanley Morgan, near Wingate, England

Application April 7, 1934, Serial No. 719,581
In Great Britain April 8, 1933

1 Claim. (Cl. 202—109)

The present invention relates to an apparatus for making gas and coke from a solid distillable fuel and has for its object to provide an apparatus which can utilize finely divided "duff" coal or "pearl coal" of pieces not larger than $\frac{1}{4}$ inch for which it is otherwise difficult to find a market. The carbonization of the coal is accomplished by mixing it with incandescent coke.

According to the invention the apparatus used 10 comprises a mechanical grate, a mixing chamber for coal and incandescent coke above and adapted to discharge on to one end of said grate, means for supplying air to said grate whereby to raise the mixture of coal and coke to incandescence, a coke hopper above, and adapted to discharge into said mixing chamber, a hopper for coal above and adapted to discharge into said mixing chamber, means for collecting incandescent coke discharged from the other end of said 15 grate, a conveyor adapted to convey part of said incandescent coke to said coke hopper from said collecting means, and means for driving off the gas generated in said mixing chamber.

The invention is illustrated in the accompanying drawings in which Fig. 1 represents a side view of an apparatus according to the invention 20 and Fig. 2 is a plan view.

An ordinary chain grate is shown at 5. It is adapted to be driven by the shaft 17 and gear 25 wheel 18 by means of the octagonal roller 19. This chain grate is caused to run faster than usual and to spill hot coke at its upper end into a hopper 6. The coke is collected in the hopper 6 and part thereof is blown by means of a jet 7 along a pipe 9 into the hot coke storage hopper 10.

The gas (air, steam or stripped gas) supplied to the jet 7 may be preheated by means not shown and fed to the jet by a blower 8.

If air is employed, and preheated, combustion 30 will occur in the pipe 9.

The hot gas thus produced consisting of carbon monoxide and carbon dioxide if air is used, carbon monoxide and hydrogen (water gas) if steam is used is returned to the grate by the pipe 35 12 where it is burnt. Before it passes to the grate, however, it is passed to a dust catcher 11, where fine dust is deposited, by the port 20. The hot coke is fed from the hot coke storage hopper 10 to the mixing chamber 3 by the mixing device 2, 40 into a mixing chamber 3 where it is mixed with fresh coal fed from the coal hopper 1. The distillation and mixing chamber 3 is closed at the bottom by the chain grate, which continuously withdraws the hot coke therein produced, the coke 45 being heated to bright incandescence by the com-

bution on the chain grate. Distillation occurs in the chamber 3, the gases and vapors produced passing out through pipe 13 to the usual collecting and purifying apparatus (not shown), 16 is the means supplying air to the chain grate, 14 is a 5 arched flue and 15 a chimney stack. The apparatus may be incorporated with a steam raising apparatus.

In this way an extremely effective gas making process becomes possible. A very rich gas is 10 evolved from the coal, and if it is desired to produce a gas containing say 400-500 B. t. u. per cubic foot, it is not even necessary to separate the coke chamber from the distillation chamber, for I find that 3000 cubic feet of air suitably discharged from a jet will lift sufficient coke to distill enough coal to produce 3000 cubic feet of gas of 1000 B. t. u. The mixture is therefore about 400-500 B. t. u.

If steam is used, to elevate the coke a continuous supply of water gas is obtained, which may 20 or may not be enriched by the use of coal.

Oil may be injected into the hot coke also to enrich the water gas.

It should be observed that I have thus all the 25 advantages of a water gas system without the complication of blowing with air alternately with steam. It is also possible to avoid the necessity of isolating the coke chamber from the distillation chamber by blowing with the stripped gas 30 itself.

The method of distillation by mixing directly hot coke with carbonaceous material is capable of the most delicate adjustment as regards operating temperature and is able to deal with almost 35 any materials that will burn. It will produce a very rich gas which may be still further enriched by spraying oil into the hot mass, or it can be adapted to produce water gas or producer gas enriched or not.

When oil is used no trouble is caused by deposition of carbon for this is burnt away on the chain grate. The thermal efficiency is very much greater than is usual in gas making plants and such heat losses as occur are amply compensated 45 for by the recovery of oil and the production of a valuable gas.

I declare that what I claim is:—

An apparatus for making gas and coke from a distillable fuel, comprising an enclosed mixing chamber of a size adapted to serve as a distillation chamber and having distributor means therein, a coal hopper above and adapted to discharge into said mixing chamber, a coke hopper above and adapted to discharge into said mixing 50 55

chamber, an inclined and enclosed endless conveyor grate having the lower end thereof disposed below said mixing chamber and adapted to receive a mixture of coal and coke therefrom, means for supplying air to said grate to raise the mixture of coal and coke to incandescence, means for collecting incandescent coke discharged from the upper ends of said grate, a compressed gas

conveyor for conveying part of the incandescent coke to said coke hopper from said collecting means, means for returning the hot gas produced in said compressed gas conveyor to said grate, and means for drawing off the gases generated in 5 said mixing chamber.

JOHN STANLEY MORGAN.
